THERMALLY ADJUSTABLE ELECTRICAL DEVICE ENCLOSED WITHIN ENVELOPES

Albert Horace Atherton, Ealing, London, England,
assignor to Electric & Musical Industries Limited, Hayes, England, a company of Great Britain

Application April 26, 1946, Serial No. 665,032
In Great Britain February 27, 1945

Section 1, Public Law 690, August 8, 1946
Patent expires February 27, 1965

12 Claims. (Cl. 315—5)

1

This invention relates to electrical devices enclosed within envelopes.

There are a large variety of electrical devices with which it is necessary to enclose within evaporated or gas-tight envelopes and in such devices it is often necessary to adjust the position of an element within the envelope from the exterior thereof. An example of a device to which the present invention is especially applicable is an electron discharge device employing a hollow resonator. Such devices employ an electron beam which is caused to pass through the resonator and such devices must therefore be enclosed within an envelope which is evacuated or gas-filled. It is often required in such devices to adjust the tuning of the hollow resonator and this operation is frequently performed by deforming or displacing a wall of the resonator. Whilst many proposals have been made for adjusting the wall of the resonator from the exterior of the envelope, such proposals usually involve the use of metallic bellows attached to the envelope so that a mechanical force from the exterior of the envelope can be communicated to the wall of the resonator to enable the position of the wall to be changed. Another example of an electrical device in which it may be required to adjust the position of an element enclosed within an envelope is an electrical condenser contained within an envelope wherein, in order to adjust the capacity of the condenser, one electrode is required to be moved relatively to another electrode of the condenser from the exterior of the envelope. Since all parts of the devices which pass through the envelope have to be sealed in a gas-tight manner to the envelope, it is not readily possible to adjust the position of elements within the envelope unless recourse be had to the use of metallic bellows, which gives rise to practical difficulties. On the other hand, in electron discharge devices employing hollow resonators it has been suggested to tune the resonator by imparting movement to a wall thereof by thermal means. For example, it has been suggested to heat and expand a rod connected to the wall of the resonator or to heat a bowed element connected to a rod in turn connected to the wall of the resonator. These prior proposals, however, suffer from the disadvantage that whilst it is possible to obtain adjustment of the wall when causing expansion of the rod or bowed element, the rate of adjustment in the opposite direction is limited by the rate of cooling of the rod or bowed element. Furthermore, the operat-

2

ing temperature must be high to give a reasonable rate of cooling so that the operating position of the wall must be at some distance from its position when the rod or bowed element is cold and it is found, in practice, that this distance is perhaps two or three times the distance over which the tuning element is required to move for a desired tuning range.

The object of the present invention is to provide an electrical device enclosed within an envelope and having improved means for effecting adjustment of an element within the envelope thermally, but in which the disadvantages mentioned above with the previously proposed thermal means are reduced or overcome.

According to one feature of the invention there is provided an electrical device enclosed within an envelope and having an element in said envelope which requires to be adjusted, wherein thermal means are provided for adjusting the position of said element, said thermal means comprising at least two expansible members and means for individually heating said members, said members being coupled to the element requiring adjustment and being so arranged that when one of said members expands it causes movement of said element in one direction and when the other of said members expands it causes movement of the said element in the opposite direction whereby movement of element in either direction can be effected on differentially heating said members. With such a construction it will be appreciated that a change in the position of the element requiring adjustment can be effected in either direction by heating one of said members more than the other, thus obviating the necessity of allowing cooling to occur before adjustment in one direction can occur. Furthermore, the position of the element requiring adjustment need not be changed when raising said members to their operating temperatures since substantially no change in the position of said element occurs until differential heating of said members is effected, with the result that the position of the element requiring adjustment with said members cold can be substantially the same as its position with said members equally hot.

The invention is particularly applicable to the tuning of hollow resonators employed in velocity-modulated electron discharge devices but is equally applicable for use in other electrical devices where it is not readily possible to adjust the position of an element owing to the presence of an envelope.

In one form of the invention said expandable members are heated by electron bombardment and in such a case one or more cathodes are provided disposed in proximity to said expandable members, control of the electrons to cause heating of said members to the desired extent being effected by the provision of control electrodes which are suitably arranged and to which potentials can be applied to control the number of electrons permitted to bombard said expandable members.

In order that the said invention may be clearly understood and readily carried into effect, it will now be more fully described with reference to the accompanying drawings which illustrate the invention as applied to an electron discharge device employing a hollow resonator and in which:

Fig. 1 illustrates diagrammatically in longitudinal section an electron discharge device employing a hollow resonator, tuning of which is effected by thermal means constructed in accordance with one embodiment of the invention.

Figure 1a is a detail plan view of a part of the device shown in Figure 1, and

Figure 2 is a diagrammatic view illustrating thermal means constructed according to another embodiment of the invention.

As shown in Figure 1 of the drawing, the reference numeral 1 indicates in cross-section a hollow resonator of a velocity-modulated electron discharge device, said resonator being arranged within an evacuated envelope 2. Disposed in proximity to the resonator 1 is a cathode 3 arranged within a cathode shield 4. The resonator 1 is supported by a plurality of support rods 5 two of which are shown in the drawing, the cathode 3 and shield 4 being carried by an insulating disc 6 also carried by the support rods 5. The support rods 5 and the elements carried thereby are in turn supported from the base or pinch 7 of the envelope 2 by support rods 8, one of which is shown in Figure 1. The device shown in the drawing is intended as a generator of self-maintained oscillations and the resonator 1 is provided with an acceleration grid 9 and a pair of grids 10, electrons emanating from the cathode 3 being accelerated by the grid 9 and caused to pass through the grids 10 where the electrons become velocity-modulated, the electrons then passing towards a reflecting electrode 11 where they are reflected and pass back through the grids 10. The device functions as stated above to generate self-maintained oscillations in known manner, the generated oscillations being fed from the resonator 1, via a concentric line 12.

In order to tune the resonator 1 the upper wall 13 of said resonator is flexible and in order to deflect said wall thermal means in accordance with the invention are provided. As shown, a pair of expandable members 14 and 15 are provided in the form of bowed strips, each strip being carried by one of two rigid rectangular supports 16, 17, said supports 16 and 17 being interconnected at their ends by brackets 18 and 19. The bowed strips 14 and 15 are welded or otherwise suitably secured at their ends to said supports 16 and 17, the latter being provided with longitudinal slots 20 and 21. The strip 14 is connected to a rod 22 which at its upper end is attached to a rigid disc 23 carried at the upper end of the support rods 5. The strip 15 is connected to a rod 24 which in turn is connected to a sleeve 25 attached to the flexible wall 13 of the resonator 1, the sleeve 25 also forming a

support for the reflecting electrode 11 which is carried by an insulating disc 26. A plan view of strip 14 and support 16 is shown in Fig. 1a, strip 15 and support 17 being identical in construction save that member 24 is affixed below strip 15 and passes through slot 20. The strips 14 and 15 have substantially the same curvature and are disposed in registry so that the distance between them parallel to the rods 22 and 24 is substantially the same throughout their lengths. Each strip is arranged to be individually heated and in the embodiment of the invention shown in Figure 1 heating is effected by bombarding said strips with electrons which emanate from an elongated cathode 27 disposed, as shown, between said strips 14 and 15, the electron emission from the surface of the cathode 27 opposite each strip 14 and 15 being controlled individually by control electrodes 28 and 29.

It will be observed from the construction shown in Fig. 1 that when the strip 15 is heated and it expands, the strip will bow further tending to move the wall 13 upwardly and when the strip 14 is heated it likewise expands and bows further causing the wall 13 to move downwardly. Providing the strips 14 and 15 are raised to substantially the same temperature no change in the position of the wall 13 will occur so that the position of this wall when the strips 14 and 15 are cold is substantially the same as its mean operating position when the strips 14 and 15 are equally heated, but as soon as differential heating of the strips 14 and 15 occurs then movement will be imparted to the wall 13 depending on the manner of the differential heating. In operating the device shown in the drawing the resonator 1 will usually be maintained at a positive potential which potential will be communicated to the strips 14 and 15 since all the parts are metallic and are not insulated from one another so that the strips will collect the bombarding electrons from the cathode 27. If the strips 14 and 15 are not electrically connected to the resonator 1, then separate leads will be required whereby the strips 14 and 15 can be maintained at appropriate operating potentials. To control the degree of the heating of each strip 14 and 15, the potentials applied in operation to the control electrodes 28 and 29 are varied, so controlling the electron emission and thus the degree of bombardment of the strips 14 and 15.

By means of the invention, movement of the wall 13 can be effected by differentially heating strips 14 and 15 thus obviating the disadvantage mentioned above in which movement of the element requiring adjustment in one direction was effected as a result of cooling.

The construction of the device shown in the drawing is particularly suitable for use in automatic frequency control, the proper frequency being obtained by suitably biasing the control electrodes 28 and 29, the bias potentials being then automatically controlled from the outputs of a push-pull pair of electron discharge devices. Alternatively, the bias potentials may be applied to the control electrodes 28 and 29 intermittently, the rate at which the potentials are applied being controlled in order to adjust the tuning of the resonator 1.

The invention is not limited to the actual construction shown in the drawing, since instead of employing a pair of bowed strips 14 and 15, it is possible to employ other constructions. For example, as shown in Figure 2 of the drawings, the rod 24 is connected to one end of a rigid bar

30 to the other end of which there is connected at right angles thereto a pair of spaced parallel expandible members 31 and 32 mounted on a rigid support 33 and which are arranged to be differentially heated. When one of the members 31 or 32 is heated the bar 30 tends to pivot about the end of the other member and when the latter member is heated the bar 30 tends to pivot about the first member, the resultant movement of the opposite end of said bar 30 being imparted to the rod 24. The arrangement shown in Figure 2 is not so advantageous as that shown in Figure 1, since it will be appreciated from Figure 2 that when both of the rods 31 and 32 are heated, movement of the rod 24 will occur, whereas with the arrangement shown in Figure 1 no movement of the rod 24 occurs until the strips 14 and 15 are differentially heated. It is not necessary to heat the expandible members 14, 15 or 31, 32 by bombarding them with electrons since other heating means may be used. For example, as shown in Figure 2, each expandible member 31, 32 is associated with a suitable form of heating coil 34, 35. The invention is not limited in its application to electron discharge devices employing hollow resonators since it can be employed in connection with any other electrical device arranged in an envelope and having an element the position of which it is required to adjust. Furthermore, the invention can also be applied to electron discharge devices employing hollow resonators in which tuning of the latter is effected by the provision of one or more plungers. If desired by suitable design bi-metallic strips may be employed for the expandible members, which bi-metallic strips will be arranged in the same manner as strips 14 and 15 shown in Fig. 1.

What I claim is:

1. An electron discharge device comprising a hollow resonator having a flexible wall whose position determines the tuning of said resonator, tuning means for said resonator comprising two metallic expandible members spaced equidistantly from each other, means mounted adjacent said expandible members for individually heating said members, a rigid link between said expandible members, another rigid link between the flexible wall of said resonator and one of said expandible members, and a sealed envelope surrounding said resonator, said tuning means, said heating means and said rigid links.

2. An electron discharge device comprising a hollow resonator having a flexible wall whose position determines the tuning of said resonator, tuning means for said resonator comprising two metallic expandible members spaced equidistantly from each other, said expandible members comprising coextensively arranged metallic strips which are bowed in the same direction and have the same curvature, as a result of which the distance between them is substantially the same throughout their lengths, means mounted in heat conducting relationship to said expandible members for individually heating said members, a rigid link between said expandible members, another rigid link between the flexible wall of said resonator and one of said expandible members, and a sealed envelope surrounding said resonator, said tuning means, said heating means and said rigid links.

3. An electron discharge device comprising a hollow resonator having a flexible wall whose position determines the tuning of said resonator, tuning means for said resonator comprising two

metallic expandible members spaced equidistantly from each other, a cathode between said expandible members for bombarding said members with electrons, a control electrode between each said expandible member and said cathode for controlling the flow of electrons therebetween, a rigid link between said expandible members, another rigid link mounted between the flexible wall of said resonator and one of said expandible members, and a sealed envelope surrounding said resonator, said tuning means, said heating means and said rigid links.

4. An electron discharge device comprising an oscillatory circuit having tuning means, said tuning means including a pair of metallic members spaced equidistantly from each other and adapted to expand upon the application of heat thereto, a cathode located between said expandible members for bombarding said members with electrons, a control electrode between each expandible member and said cathode for controlling the flow of electrons therebetween, a mechanical linkage between said metallic members, and a coupling link mounted between one of said metallic members and said oscillatory circuit.

5. An electron discharge device comprising a hollow resonator having a flexible wall, a pair of similarly bowed and coextensive metallic expandible strips spaced equidistantly from each other, said strips having the same curvature and being bowed in the same direction, a rigid link from the center of one strip to said flexible wall, and a rigid link from the center of the other strip to a stationary support, said rigid links being oppositely disposed with respect to said expandible strips, means rigidly connecting said strips to each other, and means for differentially heating said strips.

6. An electron discharge device comprising a hollow resonator having a flexible wall, a pair of similarly bowed and coextensive metallic expandible strips and spaced equidistantly from each other, said strips having the same curvature and being bowed in the same direction, a rigid link from the center of one strip to said flexible wall, and a rigid link from the center of the other strip to a stationary support, said rigid links being oppositely disposed with respect to said expandible strips, means rigidly connecting said strips to each other, and means for differentially heating said strips, said last means including a cathode positioned between said strips for bombarding the same with electrons and a control electrode between each strip and said cathode for controlling the electron flow therebetween, and a sealed envelope enclosing said resonator, said strips, said rigid links and said heating means.

7. In combination, a sealed envelope, an electrical device entirely enclosed within said sealed envelope, comprising a supporting structure sealed into a wall portion of said envelope, a resonator having fixed and adjustable elements, a fixed element of said resonator being mounted on said supporting structure, a pair of thermally expandible members equidistantly spaced from each other, one of said members being linked to said supporting structure, a rigid link mounted between said members, a further rigid link mounted between the other of said members and the adjustable element of said resonator, and means interposed between said expandible members to individually heat said members.

8. An electron discharge device comprising a supporting member, a cavity resonator having

two portions mutually adjustable with respect to each other, one of said portions of said resonator being mounted on said supporting member, tuning means for said resonator comprising two thermally expansible members equidistantly spaced from each other, one of said members being linked to said supporting member and the other of said members being linked to the remaining portion of said resonator, rigid mechanical links mounted between the ends of said expansible members, a cathode arranged between said expansible members to bombard the same with electrons and control electrodes arranged between said cathode and said expansible members to control the flow of electrons therebetween, and a sealed envelope surrounding said cavity resonator and said tuning means, said supporting member being sealed into a wall portion of said envelope.

9. An electron discharge device comprising a supporting member, a cavity resonator having two portions mutually adjustable with respect to each other, one of said portions of said resonator being mounted on said supporting member, tuning means for said resonator comprising two thermally expansible members equidistantly spaced from each other, one of said members being linked to said supporting member and the other of said members being linked to the remaining portion of said resonator, rigid mechanical links mounted between the ends of said expansible members, a cathode arranged between said expansible members to bombard the same with electrons and control electrodes arranged between said cathode and said expansible members to control the flow of electrons therebetween, and a sealed envelope surrounding said cavity resonator and said tuning means, said supporting member being sealed into a wall portion of said envelope and being separated into a plurality of conducting portions to conduct electric currents into the interior of said envelope to said resonator and said tuning means.

10. In combination, a sealed envelope and an electrical device enclosed within said envelope; said device including a rigid support and an element requiring adjustment, means adjustably mounting said element comprising two thermally-expansible members equidistantly spaced from each other, rigid means connecting said members, rigid means connecting said support to one of said members, rigid means connecting said element to the other member, and means for individually heating said members, said members being adapted to expand in the same direction when heated, whereby the adjustment of said element in either direction may be effected by

5 differentially heating said expansible members, said two thermally-expansible members and said three rigid means constituting the sole means for maintaining said element in a particular adjusted position relative to said support.

11. An electrical device including a rigid support, an element requiring adjustment movably mounted relative to said support, and means for effecting adjustment of said element comprising two thermally-expansible members, means coupling parts of said members to each other, means rigidly coupling another part of one of said members to said support, means rigidly coupling another part of the other of said members to said element, and means for individually heating said members, said members being adapted to expand in the same direction when heated, whereby the adjustment of said element in either direction may be effected upon differentially heating said expansible members, said two thermally-expansible members and said three coupling means constituting the sole means for maintaining said element in a particular adjusted position relative to said support.
12. An electrical device comprising a rigid support, an element requiring adjustment, and means adjustably mounting said element relative to said support comprising a pair of coextensive metallic expansible strips equidistantly spaced from each other, said strips having the same curvature and being bowed in the same direction, a rigid link from the center of one strip to said element, and a rigid link from the center of the other strip to said support, said rigid links being oppositely disposed with respect to said expansible strips, means rigidly connecting the adjacent ends of said strips to each other, and means for separately heating said strips.
